UNITED STATES PATENT OFFICE.

GEORGE L. BALLARD, OF NORRISTOWN, PENNSYLVANIA, ASSIGNOR TO WILDEMAN MFG. CO., OF NORRISTOWN, PENNSYLVANIA, A CORPORATION OF PENNSYLVANIA.

YARN-CHANGING MECHANISM FOR CIRCULAR-KNITTING MACHINES.

1,255,125.

Specification of Letters Patent.

Patented Feb. 5, 1918.

Application filed July 15, 1914. Serial No. 851,182.

To all whom it may concern:

Be it known that I, George L. BALLARD, a subject of the King of Great Britain, residing at Norristown, Pennsylvania, have invented certain new and useful Improvements in Yarn-Changing Mechanism for Circular-Knitting Machines, of which the following is a specification.

One object of the present invention is to provide in a multiple feed machine a plurality of strippers with controlling mechanism for each stripper which will be operated in succession to make the striping begin and end at the same wale.

15 The invention consists in the features and combination and arrangement of parts hereinafter described and particularly referred to in the appended claims.

In the accompanying drawings:

20 Fig. 1 is a plan view in the nature of a diagram showing the upper structure or knitting head partly broken away and showing a portion of the lower structure.

25 Fig. 2 is a side elevation of the invention looking from the point X, Fig. 1 toward the vertical center of the machine.

Fig. 3 is a side view and,

Fig. 4 is a plan view of a detail connection.

30 Fig. 5 is a detail side view of the controller.

Fig. 6 is a detail view of the thread clamps.

Fig. 7 is a detail view of the star wheels.

35 While features of my invention may be applied to machines of various types and in various ways, in the particular example of my invention herein disclosed, I show the invention as applied to a machine of the rotary needle cylinder type, and while my invention may be applied to machines for making various articles and tubular fabrics of various diameters, in the particular form shown it is illustrated in connection with a body machine for making, for instance, sweaters.

In the drawings, 1 indicates the rotary needle cylinder, 2 the cam cylinder. Disposed at different points, say four in num-

ber, about the needle cylinder and fixed in relation thereto are the strippers. Each stripper comprises a pair of yarn feed fingers consisting of arms *w'* and *r'* pivoted at 3 and pressed by springs 3' to their low positions for feeding their yarns to the needles. 55 The inner ends of these yarn feed fingers have curved upwardly extending portions which are each provided with two guides or openings, the yarn being led first through the upper opening or eye 4 and 60 thence inwardly through the lower eye 4' to the needles. The yarn is directed to the feed fingers by a guide 5 one for each stripper.

These guides are fixed on the dial cap 65 6, each guide having two openings, one for say a white yarn *w* and the other for a red yarn *r*. These yarn guides extend down to a point about on a level with the upper ends of the yarn feed fingers when the latter are 70 in their lower positions and they are provided with a piece of felt or fibrous material 7, against and under the lower edge of which the yarn is drawn when either yarn finger is lifted out of work, the finger when 75 so lifted having its upper eye, occupying a position some distance above the lower end of the yarn guide so that slack will be drawn when the yarn finger is raised to provide the necessary excess or slack when 80 this yarn end is introduced to the needles again. In so drawing this slack the felt, wool or other fibrous material places a drag or restraint on the yarn to prevent the yarn feed finger drawing off too much. The 85 yarn fingers may be raised to withdraw their yarns from the needles by various means but in the particular construction shown controllers or cams 8 are used one for each stripper attachment. 90

These controllers are operated each by an arm 10 connected by a link 11 with the bell-crank 12 mounted on the post 13 extending up from the base of the head and supporting the upper yoke 13' from which 95 the dial is suspended.

There is one of these bell cranks 12 for each stripper, four in the case shown, and

these bell cranks are operated *seriatim* to cause the stripers in succession to change the color of yarn fed to the needles.

The controllers 8 comprise depending 5 portions provided with inclined lower edges which work upon the outer ends of the arms carrying the yarn feed fingers. When the cam portion is turned from central position either way it will ride over either one or 10 the other of the said arms at the outer end thereof and tip the same down, thus lifting the inner end and raising the yarn feed finger, together with its yarn, from the needles, this action taking place against the power 15 of the spring 3'. When the cam shaped controller is moved from over either yarn finger arm this arm will be lowered by its spring to put the yarn carried thereby in work.

Each stiper also comprises a yarn cutter 20 and clamp. The cutter consists of a fixed shear blade 14 and a movable blade 15, the latter being pivotally mounted at 16 and being operated by an arm 17 attached to its pivot or shaft. 25 This arm is connected by a link 17' to a bell crank lever 18 on the post 13 there being one of these bell cranks for each stiper mechanism to operate its shear blades, and these shear blades, one for each of the four 30 stripers are operated in succession.

Associated with each yarn cutter is a clamp for holding the end of the yarn when raised out of work and severed by the cutter, and while this may be variously arranged and constructed, in the particular form of the invention shown it consists of a spring plate 23 held by screws 24 and overlying the cutter blades.

Each stiper has a bracket 25 for supporting the various parts thereof above described, and each bracket is held on a post 26 by a set screw 27, the post being supported in the usual cam ring.

For operating the several bell cranks 12 45 and 18 and thereby operating the yarn feed fingers and cutters I employ contact means located in part on the rotary portion of the machine and in part on the fixed portion. These contact devices may be variably constructed and arranged but in the particular construction shown I employ sets of star wheels 28 and 29 there being four sets in the present instance, one set being provided for each stiper. A description of one set will 50 answer for them all. The star wheels 28 and 29 are on shafts or drums 30 mounted in a standard 31, fixed to the stationary base ring 32 of the machine, this ring, as in usual practice supporting by standards 33, 55 the fixed base ring 34 of the knitting head. The star wheel 28 has its shaft or drum connected with a rod 35 by a pin 36 which is arranged eccentric to the center of the shaft or drum. The upper end of this rod is con-

nected to the bell crank 12 of the stiper to 65 which this particular set of star wheels belong.

The shaft or drum of the star wheel 29 has a cam 42 formed therewith or fixed thereto, and this may be formed by flattening the 70 sides of the extension of the said shaft or drum. This cam operates upon a lever 43 which lever is pivoted at 44 to the standard 31 and is pressed upwardly by a spring 45. It has a rod 46 pivotally connected thereto, 75 which rod is connected to the bell crank 18 which as above stated operates the cutter.

It may be mentioned here that the movable shear blades act in connection with the 80 spring clamp to hold the yarn, said blade at the time of cutting the yarn serving to push the end under the spring clamp plate to be held thereby, and therefore upon the 85 opening movement of the shear blade the yarn end which has been held thereby in connection with the spring clamp will be released, this taking place at the time the yarn is thrown into work.

The star wheels have each four arms or 90 points, two of these are narrow as at *b* and the other two are wide as at *c*.

For operating the star wheels (a quarter turn at each action) pins 50, 51 are provided on the rotary take-up ring 52, this ring rotating with the needle cylinder in the direction of the arrow *y* in Fig. 1. This ring is connected with the cylinder to rotate therewith by the standards or posts 53, which posts as in usual practice, furnish the supports for the take up rolls 54, Fig. 2. The pin 50 is slidably mounted in a standard or post 55 fixed to the revolving take-up ring 52 while the pin 51 is fixed by a screw 56 in a standard 57 carried by said revolving take-up ring. The sliding pin 50 is operated by a lever 58 pivoted to the pin 51 at 59, said lever being in turn operated by the pin 60 slidably mounted in a post 61 also supported on the revolving take-up ring. A cam 62 is vertically adjustable so as to locate its edge 62' to be either in the plane of the pin 60 for pushing it inwardly as the pin rides upon the inner surface of said cam or to be in the plane of travel of the pin 50 to push it inwardly. The cam is guided in its vertical movements by a post 63 and a pin 64 fixed to and extending up from the fixed base ring 32 and it is adjusted vertically by connections to a suitable pattern mechanism and while this may be of various forms, in the particular form shown these connections consist of a rod 65 and a lever 66.

The machine is shown with the white yarn *w* in work and the red yarn *r* out of work, the yarn finger *r'* having been lifted by the controller or cam 8 riding on the outer or

tail portion of said arm and tipping its inner end upwardly. The pin 50 which operates only upon the narrow teeth of the star wheel, is in its innermost position, having been moved to this position by the cam edge 62'. The pin 60 is in its outermost position but being in a low plane it will not be operated by the cam edge 62' which is now in its uppermost position. Furthermore, it will be noticed that the star wheels have been left in such position that their narrow arms are lowermost and as the pin 50 is at its inward limit it will pass these narrow arms without contacting therewith. Again it will be observed that the fixed pin 51 being only long enough to reach the wide arms *c*, this pin will likewise be ineffective in the position in which the machine is shown because the wide arms or teeth of the star wheels are above the plane of movement of this fixed pin. The pin 60, as before stated, travels in a path below that of the star wheels and has no effect thereon, the function of this pin, when operated by the cam 62', being to operate the lever 58 to project the traveling pin 50 outwardly to operate the star wheels by striking their narrow arms or teeth. Supposing the yarns are to be changed by withdrawing the white and introducing the red yarn, the pattern mechanism will move the cam 62 down so that its edge 62' will be in the plane of travel of the pin 60. As the pin 60 comes around it rides upon the cam edge 62' and is moved inwardly and through the lever 58, operates to throw the high long pin 50 outwardly, which high pin is long enough, as above stated, to reach the narrow teeth of the star wheels when so moved outwardly.

On giving the first star wheel 28 a quarter turn by contact of the long pin 50 the crank shaft of the star wheel is given a quarter turn, lifting the rod 35 half way up and this through the bell crank 12 moves the controller 8 to central position which allows the red yarn guide *r* to fall.

The high long pin 50 after operating the first star wheel and having lowered the red yarn guide *r'*, passes on to the second star wheel 29 and operates this a quarter turn by engaging with the narrow tooth thereof. This operates through rod 43 to open the cutter or shear blade by swinging the movable blade inwardly. These two actions, *i. e.* lowering the red yarn finger *r'* and opening the shear blade, releases the red yarn *r* from the clamp 23 and places it in work.

As soon as this opening of the shear blade has been completed the middle pin 51 which is shorter than the pin 50, strikes the broad tooth of the first star wheel 28 and gives this another quarter turn which has the effect of throwing out or upwardly the white yarn

guide *w'* with the result that this now enters 65 the shears to be severed and clamped. The middle pin 51 now contacts with the broad tooth of the second star wheel 29 and gives it another quarter turn with the result that 70 the shears are closed and the white thread is 75 severed and its end clamped by the thin spring plate 23. The red thread is now in work to make the stripe and the star wheels are left in the position shown in the figure, with their narrow teeth down in the path of 75 the pins and if changing of the yarns is to continue then as the machine continues the long pin 50 will operate the star wheels again by engaging their narrow teeth, and this will throw the white yarn carrier down 80 to introduce the white yarn and the red yarn carrier will be thrown up to put it out of work when the middle pin operates on the wide tooth of the star wheel 28 and the shears will be opened and closed as above described, together with the clamp.

The pin 50 may now be rendered inoperative for the continued use of the white yarn, supposing the body of the fabric to be white, therefore the cam 62 is raised to the position 90 shown to push inwardly the pin 50 so that it will not operate against the narrow teeth of the star wheels and further as the fixed middle pin 51 is not long enough to reach out to the narrow teeth but long enough only 95 to reach the broad teeth which are now above the plane of the pin, and further as the low pin 60 does not operate the star wheels at all, the machine will continue knitting white or the body fabric as long as the parts are in 100 the position to be operated by the cam 62 if this should be lowered and when so operated the pin 60 will be forced inwardly and through the lever 58 the pin 50 will be forced outwardly and thus be in position to operate 105 upon the narrow teeth of the star wheels for again changing the yarn to red yarn. The cam 62 having been lowered from the position shown into the plane of the pin 60 and having operated said pin to make the pin 50 110 effective on the star wheel remains in this position so long as changes are to be made in the colors. Thus the striping effect can be continued.

In operating the star wheels by pin 50 the 115 broad teeth of said star wheels are lowered into the plane of the fixed pin 51 which now operates them.

The sequence of operations at the stripers is to first lower the inoperative yarn finger 120 by moving the controller 8 to neutral position, next open the shears to receive the other yarn, (these operations being performed by pin 50 acting on the two star wheels in succession) next lift the other 125 yarn guide out of operation (by throwing the controller 8 in the opposite direction or rather in the same direction which it had

when returning to neutral position), and fourth close the shears, these last two operations being performed by the pin 51 acting in succession on the star wheels.

- 5 With the narrow and broad tooth star wheels the parts will be controlled to work in time, for instance, supposing one of the star wheels has been turned accidentally so that its broad tooth is lowermost while the 10 narrow tooth is lowermost on the adjacent star wheel.

This, if it be star wheel 28 which is out of time, would cause two ends or yarns to be in work at once, but this condition would 15 not continue because the star wheel would be immediately turned by contact of one of the pins with its broad tooth and thus one yarn would be thrown out and the other left in.

- When both yarns are in this condition 20 will exist only during the distance between pins 50 and 51. In other words, if either star wheel gets out of position the fixed pin 51, operating on the broad tooth of either wheel, will bring it into the position shown 25 with the narrow teeth lowermost.

The actions above described which take place at one group or set of star wheels to operate one stiper takes place in succession at all the groups of star wheels and their 30 stripers, the pins or contact members rotating with the mechanism and acting on the fixed group of star wheels to secure this successive action of the stripers.

As a result of this successive action the 35 striping will begin at the same wale in the fabric for each yarn changer and it will end at the same wale for each yarn changer.

Only one cam 62 is employed and one set of pins 50, 51, 60. This machine embodies 40 some of the features and mechanisms disclosed in my application filed May 22, 1914, #840,378.

I claim:

1. In combination in a circular knitting 45 machine, a rotary needle cylinder, a pair of yarn fingers pivotally mounted moving in vertical planes and having tail portions lying out beyond their pivots, a yarn cutter comprising a blade pivotally mounted to swing in a horizontal plane, an oscillating controller for the yarn fingers swinging about a vertical axis, arranged between the fingers and intermediate the ends of the fingers and having a cam portion working 50 on the tail portions of the fingers, star wheel mechanism on the fixed frame, horizontally movable rods one connected with the horizontally oscillating controller and the other with the horizontally movable yarn cutter, 55 connections between the rods and the star wheel mechanism including bell crank levers and vertical rods, and means for operating the star wheel mechanism, substantially as described.

- 65 2. In combination in a knitting machine,

a rotary needle cylinder, a yarn changer comprising two yarn fingers pivotally mounted moving in vertical planes and having tail portions out beyond their pivots, a pivoted controller swinging horizontally, the 70 pivot of which is arranged between the fingers and intermediate of the ends thereof, and a yarn cutter moving in a horizontal plane, a pair of star wheels turning on horizontal axes, a connection from the shaft of one star wheel to the horizontally swinging controller, a connection from the other star wheel to the horizontally movable cutter, means for moving said star wheel step by step, the connection leading to the controller 80 giving the same a step by step movement in one direction and a reverse step by step movement during one complete revolution of the star wheel, and the connection from the other star wheel serving to open and 85 close the cutter twice for each complete revolution of the star wheel, substantially as described.

3. In combination in a knitting machine a rotary needle cylinder, a yarn changer comprising two yarn fingers pivotally mounted, a pivoted controller swinging horizontally and having a cam portion to ride on the outer ends of the fingers, said controller being pivoted between the fingers, a yarn 95 cutter moving in a horizontal plane, a pair of star wheels arranged on horizontal axes, a crank pin connected with one star wheel, a connection between the crank pin and the pivoted controller comprising a vertical rod, 100 a bell crank lever, and a horizontal rod, a post on which the said bell crank lever is mounted, a cam member connected with the other star wheel, a connection between the said cam member and the yarn cutter comprising a vertical rod, a bell crank lever and a horizontal rod, said bell crank lever being mounted on the opposite side of the said post from the position of the first mentioned bell crank lever and means for operating 105 the star wheels step by step in one direction, substantially as described.

4. In combination in a knitting machine, a rotary needle cylinder, a yarn changer comprising two yarn fingers pivotally mounted, a pivoted controller swinging horizontally and having a cam portion to ride on the outer ends of the fingers, said controller being pivoted between the fingers, a yarn cutter moving in a horizontal 110 plane, a pair of star wheels arranged on horizontal axes, a crank pin connected with one star wheel, a connection between the crank pin and the pivoted controller comprising a vertical rod, a bell crank lever, 115 an arm on the axis of the pivoted controller, a horizontal rod extending inwardly from the bell crank lever to said arm, a cam member connected with the other star wheel, a connection between said cam mem- 120 125 130 135

ber and the cutter comprising a vertical rod, a bell crank lever connected thereto, a horizontal rod extending inwardly toward the axis of the machine, an arm connected with the cutter and to which said last mentioned inwardly extending horizontal rod is connected and means for operating the star wheels step by step in one direction.

5. In combination in a circular knitting machine, yarn changing means comprising a pair of yarn fingers and a cutter for one feed, a controller for operating the yarn fingers by a step by step movement in one direction, a pair of star wheels arranged side by side on horizontal shafts, connections from the shaft of one of the star wheels for operating the controller step by step in one direction and then step by step in the other direction during one complete revolution of said star wheel, connections from the shaft of the other star wheel for opening and closing the cutter twice for each step by step full revolution of said star wheel, a pair of pins traveling with a rotary part of the machine for operating each of the star wheels twice during the passing of the pins each operation giving the star wheels a quarter turn, and cam and pattern mechanism controlling the action of the pins, substantially as described.

6. In combination in a circular knitting machine, yarn changing means comprising a pair of yarn feed arms and a yarn severer, a pair of star wheels arranged on horizontal shafts, traveling contact means for operating the star wheels a half turn by step by step movements in changing and cutting the yarn, a connection extending from a crank pin on one star wheel for lowering one yarn feed arm and raising the other and a cam on the shaft of the other star wheel for opening the cutter on one quarter turn and closing the cutter on the next quarter turn of said star wheel shaft and cam, substantially as described.

7. In combination in a circular knitting machine, yarn changing means comprising a pair of yarn feed arms and a yarn severer, a pair of star wheels arranged on horizontal shafts, traveling contact means for operating the star wheels, a half turn by step by step movements in changing and cutting the yarn, a connection extending from a crank pin on one star wheel for lowering one yarn feed arm and raising the other and a cam on the shaft of the other star wheel, a lever operated by said cam, a spring for operating the lever and a rod extending from the said lever and connected with the cutter, substantially as described.

8. In combination in a circular knitting machine, a stripier comprising yarn feed fingers movable in a vertical plane, means for controlling the said fingers, said feed fingers having each two eyes, a yarn cutter

and clamp, a yarn guide extending to a point below the upper guide eye of the elevated yarn finger and restraining fiber at the yarn guide under and against which the yarn is drawn by the elevated finger to provide slack under restraint, said yarn fingers operating between the yarn guide and the point where the yarn is engaged by the clamp, substantially as described.

9. In combination in a knitting machine, a stripier comprising a pair of yarn fingers movable to and from the needles, a yarn cutter, a star wheel with connections for operating the yarn fingers, said star wheels having each broad and narrow arms alternating in position, and pins or contacts traveling with a rotary part of the machine for operating the star wheels in succession, one of said contacts being shiftable and in one position operating upon the narrow arms of said star wheels and the other of said contacts being fixed and operating upon the broad arms of said star wheels, substantially as described.

10. In combination in a knitting machine, a stripier comprising a pair of yarn fingers movable to and from the needles, a yarn cutter, a star wheel with connections for operating the yarn fingers, a star wheel with connections for operating the yarn cutter, said star wheels having each broad and narrow arms alternating in position, and pins or contacts traveling with a rotary part of the machine for operating the star wheels in succession, one of said contacts being shiftable and in one position operating upon the narrow arms of said star wheels and the other of said contacts being fixed and operating upon the broad arms of said contacts, and means for adjusting the first mentioned contact out of line with the narrow arms, the broad arms being normally out of line with the said fixed contact when the narrow arms are in position to be operated, substantially as described.

11. In combination in a knitting machine, yarn changing means, a pair of star wheels with connections for operating the said means, said star wheels having each narrow and broad arms alternating in position, a shiftable contact to engage the narrow arms, a second contact to engage the broad arms, said contacts traveling with a rotary part of the machine, a contact in a different plane from the shiftable contact and also traveling with said rotary part of the machine, a connection between the said last mentioned contact and the shiftable contact to operate one from the other and a cam shiftable in the planes of movement of said contacts to render the shiftable contact effective or ineffective on the star wheels, and pattern means for operating the cam, substantially as described.

12. In combination a rotary needle cyl.

inder, a yarn changer, connections on the fixed frame for operating the yarn changer including a star wheel, a radially shiftable pin and a fixed pin on a part of the machine 5 rotating with the needle cylinder, both of said pins operating the star wheel, a second shiftable pin on the rotary member, a lever connecting the shiftable pins whereby, when one moves outwardly radially the other 10 moves inwardly, the second shiftable pin

moving in a plane below the star wheel, and a vertically shiftable cam on the fixed frame for operating the shiftable pins, and pattern means for operating the cam, substantially as described.

GEORGE L. BALLARD.
